COMPRESSOR THROTTLING APPARATUS

Ellis E. Hewitt, Edgewood, Pa., assignor to The Westinghouse Air Brake Company, Wilmerding, Pa., a corporation of Pennsylvania

Application September 29, 1942, Serial No. 460,131

14 Claims.

(Cl. 230—2)

This invention relates to fluid compressors, and more particularly to a discharge throttling valve device for a compressor.

In order to restrain undesirable racing of a compressor operating under varying load conditions, such as a steam driven compressor of the type employed in railway air brake service, it has been proposed to provide means responsive to the receiving reservoir pressure for controlling the supply of steam or other motive power to the compressor. One form of compressor steam throttling valve device in common use, for example, is arranged to reduce the flow of the steam to the compressor while the pressure of air in the receiving reservoir is too low to provide an adequate cushion for the air pistons of the compressor, thus preventing damage to the pistons and cylinder heads, breakage of reversing valve rods, and other ill effects produced by racing of a compressor. Although steam throttling valve devices of this type have proved satisfactory under favorable operating conditions, the construction of the necessarily complicated operating elements thereof involves expense and the use of scarce strategic materials, so that economical production of valves of this class may be difficult. Furthermore, a steam throttling valve is sometimes rendered inoperative in railway service because of salts and limes precipitated out of the steam when bad water is encountered.

It is one object of my invention to provide a novel fluid throttle arrangement of simple and inexpensive construction, which may be disposed in the air discharge line of a compressor for producing a proper cushioning effect upon the compressor to prevent racing, and which is not subject to the undesirable features of the steam throttling valve just mentioned.

Another object of the invention is to provide a novel discharge throttling valve arrangement which may form an integral part of a complete compressor of the type useful in railway service.

Other objects and advantages of the invention will appear in the following more detailed description thereof, taken in connection with accompanying drawing, wherein

Fig. 1 is a diagrammatic sectional view of a portion of a compressor apparatus having the throttling valve mechanism associated therewith; and

Fig. 2 is a similar view in which a modified form of throttling valve mechanism is illustrated.

Embodiment shown in Figure 1

As shown in Fig. 1 of the drawing, there is pro-

vided a fluid compressor, indicated generally by the reference numeral 5, which may be of the steam driven type and comprises a cylinder 6 having a compression chamber 7 in which is mounted a piston 8, which is arranged for operation through the medium of a piston rod 9 by a steam actuated piston, not illustrated. It will be understood that suitable inlet valves, not shown, are provided for admitting air to the compression chamber below the piston 8 at the start of its downward stroke, and above the piston upon initial upward movement thereof, so that the piston is adapted to compress air upon movement in either direction.

Formed in a lateral extension of the cylinder 6 are upper and lower valve chambers 11 and 12, which communicate with the compression chamber 7 by way of ports 13 and 14, respectively, and which are also connected to a common discharge passageway 16. Mounted in the valve chamber 11 is a normally seated check valve element 17 which is arranged to prevent back flow of air from passageway 16 to the compression chamber. A similar check valve element 18 is disposed in the valve chamber 12 for the same purpose.

According to the invention as disclosed in Fig. 1, there is provided a discharge throttle valve device 20 comprising a casing structure 21 which is carried by the compressor cylinder 6 and which has formed therein a valve chamber 22, and a chamber 23 separated therefrom by a wall 24. The valve chamber 22 is connected by way of a pipe 41 to a receiving reservoir 42. The chamber 23 is always in communication with the passageway 16 of the compressor by way of an opening 26, and communicates with the valve chamber 22 through a restricted port 27, and also by way of a bore 28, both formed in the wall 24. Disposed in the valve chamber 22 is a valve element 30, which is adapted to engage a seat 31 formed at the upper end of the bore 28, and which has several lugs 32 slidably engaging the bore. A plunger 35 slidably mounted in a bore 36 in the casing structure 21 is provided for biasing valve element 30 toward seated position, the pressure area of the plunger being preferably greater than that of the underside of the valve element 30 within the bore 28. The plunger 35 is subject to the pressure of air in the chamber 22, and has a boss 37 which is operatively engageable with the upper surface of the valve element 30 under the force exerted by a coil spring 38, that is interposed between the plunger and a cover element 39 having screw-threaded engagement with the casing structure 21. The cover element 39 is provided with an

open port 40 for venting the space at the upper side of the plunger 35.

In operation, the compressor piston 8 is reciprocated in the usual manner for compressing air in the compression chamber 7, the air being forced past the respective check valves 17 and 18 to the discharge passageway 16. Assuming that the pressure of air in the reservoir 42 is initially below that providing the desired cushioning effect for the compressor, the force exerted by the spring 38 against the plunger 35 remains effective to hold the valve element 30 on the seat 31, so that the flow of compressed air from the passageway 16 and the chamber 23 is confined to the restricted port 27, from which the air flows through the valve chamber 22 and pipe 41 to the reservoir 42.

With the check valve 30 thus held in seated position, only a portion of the compressed air supplied to the discharge passageway 16 and chamber 23 can flow therefrom to the reservoir, because of the limited flow area of the restricted port 27, and as a result a back pressure is created for cushioning the compressor piston 8 and preventing racing of the compressor. It will thus be evident that while valve element 30 remains in seated position, the air pressure in chamber 23 must exceed that in valve chamber 22, by reason of the retardation of the flow of air through the restricted port 27 on its way to the reservoir.

After the compressor 5 has been operated for a sufficiently long interval to cause the total effective pressure of air acting upwardly on the valve element 30 and plunger 35 to exert a predetermined critical force of approximately fifty-five pounds against the spring 38, the downward force of the spring is overcome to permit initial upward movement of the valve element 30 away from the seat 31. The higher pressure of air existing in the chamber 23 then becomes effective over the larger area of the plunger 35, which is thereby quickly raised to its uppermost position to permit further upward movement of the valve element 30 with a snap action.

So long as the reservoir pressure acting against the plunger 35 remains above the predetermined critical value, as determined by the force exerted by the spring 38, the plunger is held in its uppermost position, and the valve element 30 will not be subjected to any biasing force other than that of its own weight. The full capacity of the compressor 5 is then available for maintaining the desired pressure of air in the reservoir 42.

Embodiment shown in Figure 2

In Fig. 2 of the drawing there is shown a compressor throttle valve apparatus constructed in accordance with a modified form of the invention, the various associated elements, including the compressor 5 and reservoir 42, being similar to those described in connection with Fig. 1. For insuring the desired back pressure in the compressor discharge passageway 16 there is provided a throttle valve device 50 comprising a casing structure 51 carried by the compressor cylinder 6, in which are formed an inlet chamber 52 communicating by way of a passage 53 with the discharge passageway 16, a valve chamber 54 communicating with the reservoir pipe 41, and a spring chamber 55 formed within a casing section 56 which may be bolted or otherwise secured to the casing structure 51. An always open restricted port 58 is provided in the wall

of the casing structure separating the chamber 52 from the valve chamber 54.

Interposed between the casing structure 51 and the casing section 56 is a flexible diaphragm 60, on the upper side of which is disposed a follower member 62, and on the lower side of which is provided a valve element 63 having a threaded stem 64 inserted through suitable apertures in the diaphragm and follower member for receiving an assembly nut 65. The valve element 63 is adapted to engage a valve seat 64 for controlling communication between the chamber 52 and valve chamber 54, it being noted that the area of the valve element exposed to the chamber 52, when the valve is in seated position as shown in the drawing, is less than the area of the diaphragm 60 subject to fluid pressure in the valve chamber 54. A coil spring 67 is interposed between the follower member 62 and a plug 68 having screw-threaded connection with the casing section 56, for providing a predetermined biasing force urging the valve element 63 against the seat 64. The plug 68 has formed therein an atmospheric exhaust passage 69 for venting the spring chamber 55.

The principle of operation of the throttle valve device 50 will be understood from the explanation hereinbefore presented in connection with Fig. 1. When the compressor 5 is operated to supply compressed air to the reservoir 42 while the fluid pressure therein is insufficient to provide the desired back pressure for preventing pounding of the compressor piston 8, the valve element 63 remains in engagement with the seat 64 under the pressure of the spring 67, which is effective to prevent flexing of the diaphragm 60 as long as the pressure of air in the chamber 54 is less than a predetermined critical pressure. Air compressed by the piston 8 under this condition is thus permitted to flow from the chamber 52 to the reservoir only by way of the restricted port 58, and the resultant back pressure becomes effective to cushion the compressor piston 8. When the reservoir pressure has been built up sufficiently to cooperate with the pressure of air in the chamber 52 for unseating the valve element 63, that element will be forced upwardly against the pressure of the spring 67, thus providing for free flow of compressed air to the reservoir at the full capacity of the compressor. It will be understood that the unseating movement of the valve element 63 is effected suddenly, by reason of the additional area of the diaphragm 60 that is subjected to the pressure of air from the chamber 52 after the valve element is initially moved away from its seat.

It will now be apparent that either of the two preferred embodiments of the invention may be utilized for throttling the flow of air compressed by a compressor to cushion the operation thereof, until the pressure of air in the receiving reservoir has been increased to a predetermined value, and that automatic regulation of the compressor will thereby be provided throughout a normal service life at minimum cost and without creating additional burdens of inspection and repair.

Having now described my invention, what I claim as new and desire to secure by Letters Patent is:

1. In an apparatus of the class described including a compressor and a reservoir, in combination, a throttling valve device comprising casing means including a wall interposed in the communication between the outlet of said compressor

and said reservoir, said wall having an always-open restricted passage, and valve means controlling an additional communication of larger capacity between said compressor outlet and said reservoir, said valve means being responsive to pressure of fluid in said reservoir.

2. In an apparatus of the class described including a compressor and a reservoir, the combination therewith of a throttling valve device comprising biasing means, and valve means subject to the opposing pressures of said biasing means and of fluid flowing from said compressor to said reservoir, said valve means being constructed and arranged to control the rate of such flow of fluid under pressure, thereby to maintain a back pressure cushioning operation of the compressor.

3. In an equipment of the class described including a compressor and a reservoir, the combination therewith of a throttling valve device comprising a spring, valve means subject to the opposing forces of said spring and of fluid under pressure supplied by said compressor to said reservoir, said valve means being interposed in the discharge communication of said compressor for so controlling the rate of flow of fluid therethrough as to maintain a back pressure cushioning operation of said compressor, and a restricted by-pass communication through which fluid under pressure may at any time be supplied from said compressor to said reservoir.

4. In combination, a compressor of the pressure motor actuated type having a discharge passage, a reservoir for receiving fluid under pressure delivered by said compressor at said discharge passage, and a throttle valve device interposed between said compressor discharge passage and said reservoir, comprising valve means operative when seated to cut off all but a restricted flow of fluid to said reservoir, and movable abutment means constructed and arranged to hold said valve means seated while the pressure of fluid in said reservoir is below a predetermined value.

5. In combination, a compressor of the pressure motor actuated type having a discharge passage, a reservoir for receiving fluid under pressure delivered by said compressor at said discharge passage, and a throttle valve device interposed between said compressor discharge passage and said reservoir comprising a valve element adapted to seat against the pressure of fluid in said discharge passage to cut off all but a restricted flow of fluid therefrom to said reservoir, a spring, and movable abutment means through which said spring acts to urge said valve means toward seated position, said movable abutment means being subject to the pressure of fluid in said reservoir and operative upon a predetermined increase in reservoir pressure to counteract the force of said spring.

6. The combination with a compressor having a discharge passage and a reservoir for receiving fluid under pressure delivered by said compressor at said discharge passage, of a throttle valve device interposed between said compressor discharge passage and said reservoir, comprising snap acting valve means controlling a communication through which fluid under pressure flows from said discharge passage to said reservoir, said valve means being subject to the pressure of fluid in said reservoir, and means constituting an always-open restricted communication through which fluid under pressure may at all times flow from said compressor discharge passage to said reservoir.

7. The combination with a compressor having

5 a discharge passage and a reservoir for receiving fluid under pressure delivered by said compressor at said discharge passage, of a throttle valve device interposed between said compressor discharge passage and said reservoir, comprising valve means having a pressure area subject to the pressure of fluid in said discharge passage, said valve means being operative when seated to cut off all but a restricted flow of fluid to said reservoir, and spring-pressed movable abutment means constructed and arranged to bias said valve means toward seated position, said movable abutment means having a pressure area larger than that of said valve means exposed to reservoir pressure.

10 8. In a fluid pressure apparatus of the class described, in combination, a double acting compressor of the pressure motor actuated type, a pair of check valve devices controlling communication between the respective fluid discharge ports of the compressor and a common discharge passageway, a receiving reservoir, and throttle valve means interposed in a communication between said discharge passageway and said reservoir, said throttle valve means being operative to restrict flow of fluid under pressure through said communication unless the pressure of fluid in said reservoir exceeds a predetermined value.

15 9. In a fluid pressure apparatus of the class described including a compressor and a reservoir, in combination, a casing having an inlet chamber to which fluid under pressure is delivered by the compressor and an outlet chamber communicating with said reservoir, a valve element controlling all but a restricted flow of fluid under pressure from said inlet chamber to said outlet chamber, and a spring-pressed piston normally biasing said valve toward seated position and subject to the opposing pressure of fluid in said outlet chamber.

20 10. The combination with a fluid compressor of the pressure motor actuated type, and a receiving reservoir, of a discharge throttle valve device comprising a casing carried by said compressor and having an inlet chamber to which fluid under pressure is initially delivered thereby and an outlet chamber communicating with said reservoir, a wall separating said chambers and having large and small ports, a valve controlling said large port, adjustable spring means, and a plunger engageable with said valve and subject to the opposing pressures of said spring and of fluid in said outlet chamber.

25 11. In a fluid compressor equipment of the class described including a compressor and a reservoir, in combination, a casing having an inlet chamber to which fluid under pressure is delivered by the compressor and an outlet chamber communicating with said reservoir, a valve element controlling all but a restricted flow of fluid under pressure from said inlet chamber to said outlet chamber, a spring for normally biasing said valve toward seated position, and a diaphragm interposed between said spring and said valve and subject to the pressure of fluid in said outlet chamber.

30 12. The combination with a fluid compressor of the pressure motor actuated type, and a receiving reservoir, of a discharge throttle valve device comprising a casing carried by said compressor and having an inlet chamber to which fluid under pressure is initially delivered thereby and an outlet chamber communicating with said reservoir, means providing an always-open restricted communication between said chambers, a valve controlling a larger communication between said chambers, adjustable spring means,

and a diaphragm cooperative with said valve and subject to the opposing pressures of said spring means and of fluid in said outlet chamber.

13. In a steam driven compressor including an air compression cylinder and a piston operatively mounted therein, the combination therewith of a throttling valve device comprising a casing having a discharge chamber to which compressed air can flow from said cylinder, a receiving chamber communicating with said discharge chamber through an always open port and also through a larger valve opening, and a spring chamber open to atmosphere, a valve constructed and arranged to be seated for closing said larger opening against the pressure of air in said discharge chamber, a movable abutment interposed between said receiving chamber and said spring chamber, said movable abutment being cooperative with said valve, and an adjustable spring constructed and arranged in said spring chamber to act on said movable abutment for urging said valve toward seated position, whereby said valve is operable to restrict flow of air from said compression cylinder until back pressure is established in said receiving chamber for cushioning compression strokes of said piston.

14. In a steam driven compressor of the class including an air compression cylinder having a discharge manifold, a double acting piston reciprocatively mounted in said cylinder, and check valves interposed between each end of said cylinder and said discharge manifold, the combination therewith of a valve casing carried by said cylinder and having a discharge chamber communicating with said discharge manifold, a receiving chamber communicating with said discharge chamber through an always open port and also through a larger valve opening, and a spring chamber open to atmosphere, a valve constructed and arranged for closing said larger opening against the pressure of air in said discharge chamber, a movable abutment interposed between said receiving chamber and said spring chamber, said movable abutment being cooperative with said valve, a spring mounted in said spring chamber for urging said valve toward seated position, and adjusting means for varying the pressure exerted by said spring.
